UNITED STATES PATENT OFFICE.

JOHN A. EDWARDS, OF COLUMBIANA, ALABAMA.

CHARCOAL-OVEN.

SPECIFICATION forming part of Letters Patent No. 307,928, dated November 11, 1884.

Application filed June 27, 1884. (No model.)

To all whom it may concern:

Be it known that I, JOHN A. EDWARDS, of Columbiana, in the county of Shelby and State of Alabama, have invented a new and useful Improvement in Charcoal-Ovens; and I do hereby declare that the following is a full, clear, and exact description of the same.

My invention relates to charcoal-ovens, and is an improvement upon the form shown in Letters Patent of the United States granted to me, No. 292,635.

The details of construction are hereinafter described and claimed. They are shown in the accompanying drawings, in which—

15 Figure 1 is a side elevation of the oven. Fig. 2 is a slightly-modified form of the same. Fig. 3 is a central vertical section of Fig. 1.

The oven is made of thin sheets of metal riveted together on horizontal and vertical lines, 20 and the joints are so made that the lower edge of each sheet above the first course overlaps, on the outside, the upper edge of the sheet or course next below it.

In the drawings, *a* represents the lower sheet 25 or course of sheets.

b represents the sheet or course of sheets next above it, and the lower edge of the sheet *b* is lapped on the outside of the sheet *a*. This gives the ordinary advantage of shedding water; but the principal object is that the pitch or rosin melted from the wood inside runs down the surface, filling the joints, thus rendering them air-tight. I provide around the lower edge a row or rows of ventilating-holes 35 of triangular shape with the apex at the top, and covered with corresponding doors, this

being the best mode of putting in doors and allowing the joints to be cemented when the air is shut off by plastering the three sides. When the oven is intended to be used as a 40 stationary oven, I provide one or more doors, *B*, in its walls at or near the base, for the purpose of introducing the wood or removing the charcoal. I also provide a damper-door, *C*, at the top.

In order to admit the air underneath the wood, I dig holes in the earth under the edge of the oven, as shown at *d*. These holes may be dug in as far as necessary to communicate the air freely to the wood. This makes shorter 45 brands and economizes the material, and the holes may be readily plugged with earth when it is necessary to shut off the draft.

I prefer to rivet the sheets of metal together, instead of fastening them by bolts and nuts, as the rivets can be cut whenever it may be necessary to take the oven apart for the purpose of removing it.

I claim as my invention—

A charcoal-furnace composed of sheets of 60 metal, the sheets of the upper course being lapped outside the edges of the lower, whereby the joint is made automatically air-tight in use, substantially as described.

In testimony whereof I have signed my name 65 to this specification in the presence of two subscribing witnesses.

JOHN A. EDWARDS.
